UNITED STATES PATENT OFFICE.

VICTOR HENNY, OF MARTINEZ, CALIFORNIA, AND JEAN D. SEGUY, OF CHICAGO, ILLINOIS, ASSIGNORS TO UNIVERSAL OIL PRODUCTS COMPANY, OF CHICAGO, ILLINOIS, A CORPORATION OF SOUTH DAKOTA.

APPARATUS FOR ASCERTAINING THE CHARACTERISTICS OF FLOWING LIQUIDS.

Application filed July 5, 1923, Serial No. 649,537. Renewed July 2, 1928.

This invention relates to improvements in an apparatus for ascertaining the characteristics of flowing liquids, and refers more particularly to a means for checking the gravity and temperature of hydrocarbon oils as they are withdrawn from the system.

Among the objects of the invention are to provide an apparatus whereby liquids such as oils are introduced to communicating containers, the oil being supplied to one container and maintained in a relatively stagnant pool in a communicating chamber whereby gauging instruments such as hydrometers, thermometers or the like, may be positioned in the stagnant pool and accurate readings taken, the liquid passing continuously through the pipes and being maintained at a constant liquid level by suitable apparatus; to provide an apparatus whereby agitation of the oil in the containers is reduced by permitting any gas contained in the liquid to be separated therefrom prior to its introduction into the containers, and in general to provide an apparatus of the character referred to.

Fig. 1 is a side elevational view of the apparatus with parts in section.

Fig. 2 is a view showing the method by means of which the liquid level is controlled.

Referring to the drawings, the apparatus consists of an outer container 1 in which is positioned an inner container 2 having a plurality of holes 3 in the periphery of the inner container, whereby any liquid introduced to the outer container by means of the pipe 4 will assume a common level in the two containers, due to the communicating ports 3.

The liquid is introduced through the pipe 4 from any convenient source, not shown, and has a free vertical fall into the outer container so that any gas contained in the liquid may separate therefrom, thus eliminating agitation which would normally result with the introduction of the liquid containing gas, were the liquid introduced below the liquid levels in the containers. This elimination of bubbling due to gas contained in the liquid, also does away with any foam which may collect as a result of gaseous material in the liquid.

Near the bottom of the outer container is a draw-off line 5 which has connected therewith an inverted U tube 6 which terminates as a discharge line into a lower funnel 7.

When in a vertical position, the upper portion of the U tube is somewhat above the top of the containers, but is adjustable from a vertical position at any inclination desirable, so that the liquid level in the two containers may be fixed at any desired height by rotating the inverted U tube to any desired inclination and thereby controlling the height of the liquid in the two communicating containers 1 and 2. The positioning of the U tube at various heights is best shown in Fig. 2.

To prevent a siphoning action, there is a small hole 8 drilled near the highest portion of the U tube, which supplies air to the tube, and eliminates any siphoning tendency on the part of the liquid in the inverted U tube.

There is also a drain 9 controlled by a valve 10 in the bottom of the container 2 which may be of use for drawing off water, or in case of emergency, in removing liquid from the two containers.

This double flask arrangement permits the maintenance of a relatively stagnant pool of oil in the inner container, which has a smooth liquid level by means of which accurate gravity readings may be made, although the liquid is continuously passing through the pipes. The elimination of bubbles caused by gas in the liquid, is an important feature of the invention.

The liquid overflowing through the U tube into the funnel 7, may be conducted to any suitable storage, not shown.

As stated, this device may be used in connection with any apparatus for treating liquids where it is of importance to ascertain continuously throughout the operation of the process, information concerning the characteristics of the liquid produced.

A further purpose and advantage of the invention is the positioning of an outlet or drawoff of the flowing liquid at the bottom of the cylinder or container to remove continuously all fractions of various gravities of the liquid and thereby obtain an accurate measure of the characteristics of the liquid.

The accumulation of the heavy fractions at the bottom of the apparatus would give incorrect measures or incorrect determinations of the characteristics of the liquid being tested near the upper portion, thus by continually drawing off the different types of

distillate as they come over, an accurate determination of the characteristics of each liquid may be obtained.

We claim as our invention:

5. 1. In an apparatus for testing flowing liquids, the combination with open communicating containers of substantially uniform height, of means for introducing a liquid to one of said containers whereby a relatively 10 stagnant testing pool of liquid is maintained in the communicating container, an overflow from the first mentioned container for maintaining a liquid level in the two containers.
15. 2. In an apparatus for testing flowing liquids, the combination with communicating liquid containers, one positioned inside of the other, and having a common liquid level, of means positioned above the liquid level for introducing liquid to the outer container,

whereby a relatively stagnant pool is maintained in the inner container, a liquid level controlling means connected with the outer container, and means for withdrawing liquid from the inner pool.

3. In an apparatus for testing flowing liquids, the combination with open communicating liquid containers one positioned inside of the other and having a common liquid level, of means positioned above the liquid level for introducing liquid to the outer container whereby a relatively stagnant pool is maintained in the inner container, a liquid level controlling means connecting with said containers, and independent means for withdrawing liquid from each of said containers.

VICTOR HENNY.
JEAN D. SEGUY.
